CLAIM

The ornamental design for a housing for radio receiver components or the like, as shown and described.

DESCRIPTION

FIG. 1 is a front elevational view of a housing for radio receiver components or the like showing my new design, with the pattern of small circles partially shown being continuous within the area of the broken line larger circle;

FIG. 2 is a left side elevational view;

FIG. 3 is a right side elevational view;

FIG. 4 is a top plan view;

FIG. 5 is a bottom plan view; and

FIG. 6 is a rear elevational view.
